UNITED STATES PATENT OFFICE.

ROBERT H. LAWSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

LASTING MACHINE.

Original application filed May 9, 1923, Serial No. 637,749. Divided and this application filed December 24, 1928. Serial No. 328,265.

The present invention relates to the lasting of shoes, and is herein disclosed as embodied in an automatic lasting machine of the type designed to last successive portions of each side of a shoe upper progressively.

The primary object of the invention is to provide a novel and improved mechanism for lasting shoe uppers which will be efficient and reliable in operation and particularly well adapted to press the upper snugly into the required position and secure it in this position to the sole of the shoe.

With this object in view, the several features of the invention consist in the devices, combinations, and arrangement of parts hereinafter described and claimed which together with the advantages to be obtained thereby, will be readily understood from the following description taken in connection with the accompanying drawings in which Fig. 1 is a view in side elevation of a side lasting machine embodying the several features of the invention, a portion of the casting being broken away to show underlying parts; Fig. 2 is a view in left side elevation partly in section of that portion of the head of the machine which supports and actuates the upper lasting devices; Fig. 3 is a detail view in right side elevation showing the lasting devices; Fig. 4 is a detailed view partly in section of a portion of the mechanism shown in Fig. 3, but with the parts in a different position; Fig. 5 is a view similar to Fig. 4, showing the parts in a still different position; and Fig. 6 is a detail view looking from the left of Fig. 4.

For a disclosure of the complete machine and for a detailed description thereof, reference may be had to the inventor's pending application Serial No. 637,749, filed May 9, 1923, of which the present application is a division. The machine is almost entirely automatic in operation and comprises means for working the upper over the last at opposite sides of the shoe simultaneously, means for securing the upper to the insole, and means for relatively moving the lasting devices and the shoe to transfer the point of operation along the shoe. A jack is provided to support the shoe, and two sets of grippers and stitch forming devices are arranged to act simultaneously at opposite sides of the shoe to work both sides of the shoe upper progres-

sively over the last, and to sew the upper to the rib of the insole. The gripper and stitch forming devices, as more fully set out in the above-mentioned application, are mounted on two supports which are movable in and out towards and from the center line of the shoe bottom and which may be rotated so that the lasting and sewing devices are maintained at all times in operative position as the points of operation are transferred along the shoe.

In carrying out the present invention, a wiper or gripper is provided to cooperate with each set of grippers so as to press the upper snugly into the angle formed by the rib and feather of the insole and hold it accurately in position during the operation of the sewing devices.

Referring to the drawings, the jack of the illustrated machine comprises a hollow spindle 8 the upper end of which carries the heel and toe supports for the shoe and the lower end of which is mounted, by means of a gimbal joint, on a supporting arm 12 forming a part of the jack supporting structure. The supporting arm 12 is mounted at its rear end to swing vertically on a support 14 which is in turn mounted to swing about a substantially vertical axis in a frame 16 which is pivotally mounted at its lower end in the machine base so as to be capable of swinging about a horizontal axis. Feeding movements are imparted to the jack to present different portions of the work successively to the lasting devices through connections which include the lever arm 18 and link 20 connected to the toe portion of the jack. The lever arm 18 and the jack supporting structure are actuated to impart feeding and tipping movements to the jack to present the work properly to the lasting devices from cams generally indicated at 22 on the pattern cam shaft 24.

The lasting devices comprise upper stretching gripping jaws 26 and 28 arranged to act upon the upper at each side of a shoe. Each of the grippers is mounted upon a support and upon each support is also mounted a wiper 30 adapted to cooperate with the corresponding set of stitch forming devices comprising a main needle 32, a looper needle 34, and a loop retainer 36.

Each support for the lasting devices comprises a cylindrical portion 38 from the lower

end of which flanges project downwardly, to which are secured downwardly extending parallel plates 40 and 42. To the lower end of the plate 40 is secured a block 44 which is shaped to form a presser foot arranged to bear against the surface of the sole of a shoe presented to the machine and engage the inner surface of the sewing rib so as to constitute a channel guide. The presser feet act as abutments to engage the sole surface near each edge and thus hold the sole against the last bottom and also resist the strain of the grippers on the work. As the shoe is moved longitudinally to transfer the point of operation of the lasting devices along the shoe, the channel guides are pressed yieldingly against the inner surface of the rib at opposite sides of the shoe, and thus position the grippers and sewing devices properly as the shoe sole varies in width. To permit the channel guides and the supports to which they are secured to move towards and from each other, the cylindrical portion 38 of each support is mounted in a carrier block 46 which is secured to bearing studs or trunnions 48 and 50 mounted to turn in the overhanging side walls 52 of the machine frame. The hubs of the blocks 46 which receive the pivot studs 48 are provided with arms 56 extending laterally towards each other and provided with intermeshing segmental gears 58. The supports for the upper stretching and stitch forming devices and the channel guides secured thereto are thus compelled to move towards and from each other in unison so that the channel guides, by contacting with the sewing rib of the shoe, not only control the position of the upper stretching and stitch forming devices laterally of the shoe, but also determine the lateral position of the shoe in the machine. Spring means are provided which tend to move the supports apart and thus hold the channel guides yieldingly in engagement with the inner surface of the sewing rib.

By reason of the manner in which the cylindrical portion 38 of each support is mounted in the carrier block 46, each support is capable of a rotary or turning movement about an axis substantially perpendicular to the surface of the shoe sole. This construction permits the supports to be rotated or turned, as the point of operation of the lasting and sewing devices is transferred along the shoe, to cause the main sewing needles 32 to operate in paths substantially normal to the sewing rib. These movements also rotate the grippers so that the upper engaging surfaces of the gripping jaws are substantially parallel to the edge of the shoe upper and are thus enabled to grasp the upper with certainty and to act on the upper to the best advantage. Each support is held in place in a carrier block 46 between a flange at the lower end of the cylindrical portion 38 and a ring 60 clamped upon the upper end of the cylindrical portion.

From each ring 60 a stud 62 extends which is actuated by a rod 64 shown in section in Fig. 3 of the drawings from the pattern mechanism of the machine through intermediate connections which are fully described and illustrated in the applicant's above-mentioned application to give the supports for the upper stretching and stitch forming devices the desired rotary positioning movements to compensate for the edge curvature of the shoe sole or of the sewing rib as the point of operation is transferred along the shoe.

The inner jaw 26 and the outer jaw 28 of each pair of grippers are pivotally connected together at 68. The jaw 26 has a plate-like portion extending a considerable distance above the pivot 68 which is provided with a laterally extending pin 70 about midway its length and with a vertical slot 72 at its upper end. The pin 70 engages an inclined guiding surface 74 formed in one of the plates 40 and 42 and the slot 72 is engaged by a guiding pin 76. The gripping jaw 26 is thus mounted between the parallel plates 40 and 42 of the support so that it is capable of an upward and downward movement away from and towards the shoe sole. The jaw 28 of each gripper is also provided with an upwardly extending plate-like portion, and in this portion of the gripper and in the corresponding portion of the gripper 26 are formed slots 78 and 80 arranged at an angle to each other and engaged by a pin 82. The arrangement of the slots 78 and 80 is such that an upward movement of the pin when the grippers are open and in their lowest position will first close the gripping jaw 28 upon the jaw 26 and then move the jaws bodily upward. To cause the gripping jaws to be closed before an upward movement takes place, a friction device is provided which comprises two friction disks indicated at 84 loosely mounted on the guiding pin 76 and held yieldingly in contact with the upper end of the gripping jaw 26 by means of a spring. As a strain is exerted upon the upper during the upward movement of the jaws, the jaws are permitted to swing into the line of the strain exerted upon the upper, the swinging movement taking place around the pin 76 as a center. The grippers thus act to the best advantage upon the upper and draw it tightly to the sides of the last.

In order to actuate the grippers to pull simultaneously upon the opposite sides of the shoe upper, each pin 82 is mounted on the lower end of a link 86 which is connected at its upper end to a cross head 88 mounted to slide in the cylindrical portion 38 of the support. This portion of the support is made hollow to receive the cross head 88 which is semi-cylindrical in shape and which has a bearing against the inner wall of the cylindrical portion 38 and against a corresponding cross head forming a portion of the mechanism for actuating the main thread

needle of the sewing mechanism. The cross heads 88 are in turn connected through rods 90 to the corresponding ends of a cross head or yoke 92 which is actuated from a cam on the shaft 94 through a cam lever 96, the rear end of which is engaged by the cam on the cam shaft and the forward end of which is connected to the cross head 92 by means of a lever 98. The lever 98 is pivotally mounted on the forward end of the lever 96 and has its forward end pivotally connected to the cross head 92 and its rear end connected to a vertical rod 100, the lower end of which is attached to a spring 102. With this construction, an upward movement of the forward end of the lever 96 acts through the lever 98 to exert a yielding upward pull upon the cross head 92. Adjustable stops indicated at 104 are provided to limit the movement of 20 the lever 98 with relation to the cam lever 96. To guide the cross head 92 in its up and down movements, it is connected at its upper end by means of a parallel motion link 106 to an arm 108 pivotally mounted on the frame 25 of the machine, and of a length equal to the forward end of the lever 96. The arm 108 and the forward end of the lever 96 are connected by a link 110.

The main thread needles 32 are carried on 30 corresponding yokes or carriers 112 which straddle the gripping jaws 26 and 28 and are supported by pivot studs 114 near the lower ends of the side plates 40 and 42. Each needle carrier is oscillated through a connecting link 116, the lower end of which is pivoted to the carrier and the upper end of which is carried by a cross head 118 similar to the cross head 88 and mounted in a similar manner in the cylindrical portion 38 of 35 the support for the upper stretching and stitch forming devices. Each cross head 118 is connected to the cross head 120 mounted to move above the supports for the upper stretching and stitch forming devices beside 40 the cross head 92. The cross head 120 is actuated from a cam on the actuating shaft 94 through a lever 122, the rear end of which is engaged by a cam on the shaft, and the forward end of which is pivotally connected to the cross head. To guide the cross head during its up and down movements, it is connected to the frame of the machine by a parallel motion link 124.

The sewing mechanisms, in addition to the 55 main thread needles 32, include the looper needles 34, the loop retainers 36 hereinbefore mentioned, and also take-ups consisting of levers 125 which act to set the stitches when the needles are withdrawn from the work 60 and while the wipers are in pressing position. These parts are arranged and actuated as in the machine of applicant's pending application above referred to and inasmuch as they are not illustrated in detail herein will 65 not be specifically described.

Coacting with each pair of grippers, a wiper or presser is provided for pressing the upper snugly into the angle formed by the rib and feather of the insole. Each of these wipers consists of the substantially horizontally arranged plate-like portion of an arm or lever 126 pivotally mounted at 128 at the side of the plate 40 of a support for the lasting devices. The arm 126 extends downwardly from its pivot 128 parallel to the face of 70 the plate 40 and then curves towards the left, so as to bring the portion of the arm forming the wiper into a position to engage the upper in line with the channel guide or presser foot 44 transversely of the shoe. The 75 wiper is arranged to move inwardly towards the center line of the shoe and during such movement engages the upper and presses it into the angle formed by the feather and rib of the insole. During this movement of the 80 wiper, the jaws of the gripper are actuated to release the upper sufficiently to permit the stock required to fit into the angle to be supplied from the portion held by the gripper. The wiper completes its movement ahead of 85 the main needle 32, so that the needle does not penetrate the upper until the upper has been fitted into the shoulder of the insole by the wiper. During the retracting movement 90 of the needle, the wiper remains in engagement with the upper and holds the upper firmly pressed into the shoulder of the sole until the take-up has acted to set the stitch. To guard against any displacement of the 95 shoe sole during the action of the wipers, the 100 sole engaging surfaces of the presser feet are provided with corrugations.

For imparting the above-described motions to the wipers, each wiper arm 126 is provided with a roll 130 arranged to be engaged 105 by a cam surface 132 at the free end of an arm 134. The arm 134 has formed thereon a pivot stud 136 which is mounted in the plate 40 of a support for the lasting devices, and to this stud 136 is rigidly secured an arm 138. 110 The arm 138 at its free end is provided with a slot arranged to be engaged by a stud 140 at the pivotal connection of a needle carrier 112 with its actuating link 116. The shape and arrangement of these parts is such that 115 the movements above described are imparted to the wipers from the needle actuating mechanism. A spring 142 acts upon the wiper arm 126 to maintain the roll 130 in contact with the cam surface 132.

The invention having been thus described, what is claimed is:

1. A lasting machine having, in combination, an upper stretching gripper having an updraw movement, a wiper movable into engagement with the stretched upper to press the upper into the angle formed by the rib and feather of the sole, mechanism for sewing the upper to the rib, and means for actuating the gripper, wiper and sewing mech- 125 130

anism to last progressively a shoe upper as the point of operation is transferred along the shoe.

2. A lasting machine having, in combination, an upper stretching gripper having an updraw movement, a wiper movable into engagement with the stretched upper to press the upper into the angle formed by the rib and feather of the sole, means for actuating the gripper to yield stock to the wiper, mechanism for sewing the upper to the rib, and means for actuating the gripper, wiper and sewing mechanism to last progressively a shoe upper as the point of operation is transferred along the shoe.

3. A lasting machine having, in combination, an upper stretching gripper having an updraw movement, a wiper movable into engagement with the stretched upper to press the upper into the angle formed by the rib and feather of the sole, means for causing the gripper to release the upper during the pressing movement of the wiper, mechanism for sewing the upper to the rib, and means for actuating the gripper, wiper and sewing mechanism to last progressively a shoe upper as the point of operation is transferred along the shoe.

4. A lasting machine having, in combination, an upper stretching device, a wiper movable into engagement with the upper to press the upper into the angle formed by the rib and feather of the sole, mechanism for sewing the upper to the rib comprising an eye pointed needle arranged to pierce the upper and rib from the outside and a take-up acting to set the stitch when the needle is out of the work and while the wiper is in pressing position, and means for actuating the stretching device, wiper and sewing mechanism to last progressively a shoe upper as the point of operation is transferred along the shoe.

5. A lasting machine having, in combination, an upper stretching device, a wiper movable into engagement with the upper to

press the upper into the angle formed by the rib and feather of the sole, mechanism including a needle and cooperating devices for sewing the upper to the rib, connections for actuating the wiper from the needle actuating mechanism, and means for actuating the stretching device, wiper and sewing mechanism to last progressively a shoe upper as the point of operation is transferred along the shoe.

6. A lasting machine having, in combination, an upper stretching gripper having an updraw movement, means for supporting said gripper permitting it to move into line with the strain exerted on the upper, a wiper movable to press the upper into lasted position, securing devices, and means for actuating said gripper, wiper and securing devices to last progressively a shoe upper as the point of operation is transferred along the shoe.

7. A lasting machine having, in combination, an upper stretching gripper having an updraw movement, means for supporting said gripper permitting it to move into line with the strain exerted on the upper, a guide for the gripper during its movement towards the shoe, a wiper movable to press the upper into lasted position, securing devices, and means for actuating said gripper, wiper and securing devices to last progressively a shoe upper as the point of operation is transferred along the shoe.

8. A lasting machine having, in combination, lasting devices, means for actuating said devices to stretch progressively an upper over a last as the point of operation is transferred along the shoe and secure the upper to the rib of a sole placed on the last, and a presser foot provided with corrugations arranged to engage the sole inside of the rib.

In testimony whereof I have signed my name to this specification.

ROBERT H. LAWSON.
